UNITED STATES PATENT OFFICE.

ALVA B. CHUBBUCK, OF JANESEVILLE, WISCONSIN.

ADVERTISING-WHEEL.

SPECIFICATION forming part of Letters Patent No. 690,132, dated December 31, 1901.

Application filed July 23, 1901. Serial No. 69,438. (No model.)

To all whom it may concern:

Be it known that I, ALVA B. CHUBBUCK, a resident of Janesville, in the county of Rock and State of Wisconsin, have invented certain new and useful Improvements in Advertising-Wheels; and I do hereby declare the following to be a full, clear, and exact description of the invention, such as will enable others skilled in the art to which it appertains to make and use the same.

My invention relates to an improved advertising-wheel, the object of the invention being to provide an advertising-wheel which will be so mounted as to permit it to be turned by the current of a stream to display a number of advertisements.

A further object is to provide a float and mechanism thereon operated by the current of the stream to display a large amount of advertising matter.

A further object is to provide an advertising-wheel having means for supporting it on a stream of water with improved means for holding each paddle or blade of the wheel in an upright position long enough to display the sign or advertisement thereon.

With this object in view the invention consists in certain novel features of construction and combinations and arrangements of parts, as will be more fully hereinafter described, and pointed out in the claims.

In the accompanying drawings, Figure 1 is a front view illustrating my improvements. Fig. 2 is a top plan view, partly in section. Fig. 3 is a side view. Fig. 4 is a view illustrating the castings 5, and Fig. 5 is a detail view of one of the wheel blades or paddles.

11 represent parallel timbers spaced apart and connected at their ends by boards 2, forming a float and the support for my improvements, which will now be described.

On timbers 1, about their center, bearings 3 are secured and support a rotary shaft 4, on which castings 5 are secured by set-screws 6. These castings 5 have the general shape of a Maltese cross, and the four arms or members thereof are provided with sleeves 5^a to receive the tubular frame 7 of the paddles or blades on the main advertising-wheel, and said frames are secured in the sleeves by set-screws 8. To the frames 7 sheet-metal plates

9 are secured by bending the edges thereof over the tubular frame.

Vertical shafts 10 are mounted centrally on timbers 1 and are provided between their ends with shoulders or collars 11, forming supports for advertising-wheels 12. The upper ends of these shafts 10 are supported in bearing-sleeves 10^a at the ends of a tubular frame 14, secured on the float, and a transverse rod 13 is bent at its ends and projects into bearing-sleeves 10^a and holds the shafts in a vertical position.

The wheels 12 are constructed precisely like the main wheel, except that each blade of the wheels 12 is provided with downwardly-projecting pins or lugs 13 in the path of the paddles of the main wheel, so that when the latter is turned by the current it will also turn the small wheels a quarter-turn, as will more fully hereinafter appear.

A coiled spring 12^a is provided on each sleeve 10^a and bears against the wheels 12 to act as a friction-brake and limit the turning of the wheels.

On each of the blades of the main wheel shallow metal cups 15 are secured, and air collects in the same and serves to temporarily retard the movement of the paddle through the water, hence holding the blade in a vertical position for a few moments—long enough to enable the advertisement thereon to be clearly read. These cups 15 are made with small perforations 16 to permit the air to escape and also to permit the water to run out, the weight of the water assisting to retard the revolution of the wheel.

To each blade of the main wheel metal plates 17 are secured and are adapted to have advertisements printed thereon. These plates display their advertisements when the paddle is in a vertical position and in the water, as clearly shown in Fig. 1.

The operation of my improvements is as follows: The float is anchored in a convenient place in the stream with the longitudinal timbers 1 lying in the direction of the current and the upper vertical blade turned with its cup pointing upstream and the advertising matter looking downstream. When a paddle is moved by the current into an upright position, so as to display the sign or advertise-

ment thereon, the paddle in advance of the upright paddle will be entering the water, and as the cup 15 on such paddle is full of air it will retard the revolution of the wheel until 5 the air is exhausted from the cup through the perforations 16 therein and the paddle in rear of the upright paddle will be emerging from the water with its cup 15 full of water, which will serve as a counterbalance-weight 10 to assist in holding the upright paddle in such position until the water is exhausted through the perforations in said cup, or, in other words, long enough to permit the reading of the advertisement on the upright paddle, and 15 hence it will be seen that the cups not only serve as air-chambers to halt the wheel, but also serve as water-chambers, the weight of which when filled also serving to halt the wheel and prevent for a moment its being turned by the current of the stream. The 20 number of perforations and the size thereof and the size of the cups can be regulated according to the current of water, as in very swift currents a large cup with small and few perforations is required, while in slowly-moving currents small cups and a larger 25 number of perforations will be necessary. As the blades of the main wheel pass between the vertical shafts 11 they will strike against 30 the fingers 13 on the blades of the smaller wheels 12 and turn the latter a quarter-turn to display the several advertisements thereon.

Various slight changes might be resorted to in the general form and arrangement of 35 the several parts described without departing from the spirit and scope of my invention, and hence I would have it understood that I do not wish to limit myself to the precise details set forth, but consider myself at liberty 40 to make such slight changes and alterations as fairly fall within the spirit and scope of my invention.

Having fully described my invention, what I claim as new, and desire to secure by Letters 45 Patent, is—

1. In an advertising-wheel, the combination with a float, of a wheel mounted to revolve thereon, and cups on the paddles or blades of the wheel to retard its rotation.

50 2. In an advertising-wheel, the combination with a float, of a wheel mounted thereon and adapted to be turned by the current of the stream, and a cup on each paddle of the wheel

to retard its movement through the water and having perforations therein for the escape of 55 the air and water.

3. In an advertising-wheel, the combination with a float adapted to be anchored in a running stream, of an advertising-wheel mounted on the float and adapted to be turned by the 60 current, and other advertising-wheels mounted on the float and adapted to be turned by the first-mentioned wheel.

4. In an advertising-wheel, the combination with a float adapted to be anchored in a running stream, of an advertising-wheel mounted on the float and adapted to be turned by the current, upright shafts on the float at each side of said wheel, advertising-wheels on said shafts, downwardly-projecting lugs or fingers 70 on the blades or paddles of said last-mentioned wheels to be struck by the blades or paddles of the first-mentioned wheel so as to turn all of said wheels by the movement of the stream's current. 75

5. In an advertising-wheel, the combination with a float, of a shaft on said float mounted to rotate, cross-shaped castings secured on said shaft having sleeves thereon, paddles comprising tubular frames adapted to be secured in said sleeves by set-screws, sheet-metal plates bent over said frames, and cups on said paddles or blades having perforations 80 therein.

6. In an advertising-wheel, the combination with an open float, of a paddle-wheel mounted to rotate in said float and adapted to contain advertisements on one side of its blades or paddles, advertising-plates on the opposite sides of said blades at their inner ends, vertical shafts, advertising-wheels on said shafts, springs bearing on said last-mentioned wheels to serve as friction-brakes, a frame adapted 90 to hold the shafts vertical, and pins or fingers on the blades of the last-mentioned wheels in 95 the path of the first-mentioned wheel so as to permit the turning of all of said wheels by the current of the stream.

In testimony whereof I have signed this specification in the presence of two subscribing witnesses.

ALVA B. CHUBBUCK.
